UNITED STATES PATENT OFFICE.

HAROLD P. MUELLER, OF MILWAUKEE, WISCONSIN, ASSIGNOR TO L. J. MUELLER FURNACE CO., OF MILWAUKEE, WISCONSIN, A CORPORATION OF WISCONSIN.

DESIGN FOR A HEATER.

Application filed March 5, 1925. Serial No. 12,594. Term of patent 14 years.

To all whom it may concern:

Be it known that I, HAROLD P. MUELLER, a citizen of the United States, residing at Milwaukee, in the county of Milwaukee and State of Wisconsin, have invented a new, original, and ornamental Design for Heaters, of which the following is a specification, reference being had to the accompanying drawing, forming part thereof.

In the drawing, the figure is a perspective view of the heater, showing my new design.

I claim:

The ornamental design for a heater, as shown.

HAROLD P. MUELLER.
